APPARATUS FOR RAMMING FLASKS

Murray G. Clay, Chicago, Ill., assignor, by mesne assignments, to Pettibone Mulliken Corporation, a corporation of Delaware

Application June 7, 1945, Serial No. 598,145

8 Claims. (Cl. 22—36)

1

The invention relates to filling flasks with sand for molds.

In ramming flasks with sand by means of sand projectors in foundry installations, it is sometimes advantageous, particularly where large volumes of sand are projected into the flasks, to provide stationary tanks for the backing and facing sand used, and to feed the sand to a power-driven projector which travels on a track on the foundry floor to successively ram rows of flasks, by a stationarily mounted conveyor extending along the track, the projector being adapted to travel along the conveyor to receive a constant supply of sand for delivery into the flasks. It is also advantageous to provide a seat or support for the operator which is movable with the projector, so the operator can observe the distribution of the sand in the flasks, and to control the operation of the sand-delivery mechanism and the projector by the operator. It is frequently necessary to use different kinds of sand, such as facing and backing sand and to stop the projector and sand delivery when the projector is moved from flask to flask or for other purposes. In these installations, it is also desirable to operate the projector at different speeds for varying the density of the sand in the flask and, for this purpose, it is necessary to vary the volume of sand delivered to the projector by the sand-delivery system. A desideratum is to control the operation of the motors for driving the projector and for delivering sand from stationary tanks by mechanism within reach of the operator mounted on the projector.

One object of the invention is to provide a sand-delivery mechanism which is controlled by the operator on the portable sand projector so that he may conveniently control the operation of the projector, the sand-conveyor, and the feeding mechanism which delivers the sand from stationarily mounted tanks to the projector. When the sand-system is thus controlled, it is not necessary to have an additional or assistant operator for controlling the motors which operate the sand-delivery system and the operator for the projector has complete and quick control of the sand-feeding system, as well as the sand projector.

In these installations, it is necessary to use trolleys for supplying electric current to the electric motors on the projector and it is desirable, in the control of the sand-delivery mechanism by the operator on the projector, to use a minimum number of trolleys.

Another object of the invention is to provide

2

control mechanism on the projector for the motors of the sand-delivery system through a single additional trolley and which controls the starting of the motors for feeding different kinds of sand and different volumes of the sand to the projector.

Another object of the invention is to provide simple and efficient switching mechanism for controlling the operation of the motors for driving the sand projector, the sand feeding mechanisms, and the sand-conveyors.

Other objects of the invention will appear from the detailed description.

The invention consists in the several novel features which are hereinafter set forth and are more particularly defined by claims at the conclusion hereof.

In the drawings: Fig. 1 is a plan of an installation comprising an overhead stationarily mounted sand-delivery system and a sand projector mounted to travel over the foundry floor and to be supplied with sand from said system.

Fig. 2 is a side elevation of the projector and sand-delivery system. Fig. 3 is a section of one of the tanks from which sand is discharged to the sand-conveying mechanism. Fig. 4 is a diagram of the switch mechanisms and electrical connections for controlling the sand-delivery system and the projector. Fig. 5 is an end elevation of the projector and the switch mechanism mounted thereon. Fig. 6 is a section showing the wheeled supporting frame for supporting the projector mechanism. Fig. 7 is a section taken on line 7—7 of Fig. 6.

35 The invention is exemplified in an installation which comprises a portable frame or carriage o' which is supported on flanged wheels o^3 . Wheels o^3 are adapted to travel on a rail o^2 . The upper end of carriage o' is provided with wheels o^4 which are adapted to travel in the channel of a rail o^5 . Rails o^2 and o^5 form a track which extends longitudinally of the bay of the foundry in which the flasks are to be rammed. The carriage constitutes a portable support for the projector mechanism. The carriage is usually equipped with an electric motor s and a belt-drive s' for driving one of the wheels o^3 to propel the carriage and projecting mechanism carried thereby over the foundry floor.

50 A rotary sand projector o is mounted to travel with the carriage so that it can be moved for ramming flasks distributed over the floor of the foundry. The casing of the sand projector o is fixedly supported by a jib 12 which is pivotally supported at the outer end of an arm 13 which

is pivoted to swing horizontally in a housing 14 so that the projector, by the compound or independent swinging of said jib and arm, may be moved over flasks on the floor of the foundry to distribute the sand throughout all portions of the flask. Housing 14 is supported by parallel arms 15 and 16 which are pivoted to housing 14 and the supporting frame o' for vertical adjustment of said housing and the projector. A seat 24 for the operator is mounted adjacent the end of the casing or projector o so the operator can observe the distribution of sand in the flasks. The swinging movements of jib 12 and arm 13 may be controlled by a hand lever 27 and hydraulic mechanism (not shown) of the type exemplified in Patent No. 2,339,001. An endless driven conveyor 17 which is mounted to swing with jib 12, is adapted to feed sand through an opening in the inner side of the housing of projector o into the path of a rotary blade, as is well understood in the art, for projection into the flasks. An endless driven conveyor 18 mounted to swing with arm 13 is adapted to convey sand onto the belt 17. An endless driven conveyor 19 is adapted to receive sand from a conveyor extending over the track o⁵ and deliver it onto the conveyor 18. Conveyors 19, 18 and 17 are adapted to continuously deliver sand to the projector for projection into the flasks. A motor g is connected to drive the projector blade in the housing of the projector o. Motor g is of the two-speed type and adapted to drive the projector at two predetermined speeds, for example, 1200 and 1800 R. P. M., to vary the density of the sand rammed into the mold, as desired for different work. A starting relay (Fig. 4) comprising magnets g', g² is adapted to operate two three-set switches to control the starting and operation of motor g. When a hydraulic system is used for shifting the jib 12 and arm 13 for moving the projector over the flask, a motor h (Fig. 4) is provided for forcing oil under pressure to the control mechanism, as exemplified in the aforesaid Patent No. 2,339,001. A starting relay comprising a magnet h' controls the operation of the motor h.

The overhead sand-delivery system for supplying sand to the projector comprises a tank 10 for holding a supply of facing sand; a pair of tanks 11 and 11^a each for holding a supply of backing sand; an endless conveyor 9 adapted to receive sand from any of the tanks 10, 11 and 12; and an endless conveyor 9^a which receives sand from conveyor 9 and parallels the path of travel of the carriage o' for the projector. A strike 8 is mounted to travel with the frame o' and to engage the sand on the conveyor 9 and deflect it onto the end of the conveyor 19 below said conveyor. Tanks 10, 11 and 11^a and conveyors 9 and 9^a are supported by a suitable framework 7 at a higher level than frame o' so that sand will be delivered by gravity onto the conveyor 19.

Each of the tanks 10, 11 and 11^a is provided with a rotatable bottom or disk r and a discharge chute r' through which the rotatable bottom feeds the sand in regulated quantity into a hopper r² which deposits the sand onto the conveyor 9. Each bottom r is driven by an electric motor through reducing gearing r³, a bevel pinion r⁴ and a bevel gear r⁵ fixed to the bottom. A two-speed electric motor a is provided for driving the gearing which drives the disk r under tank 10 for feeding facing sand from said tank onto the conveyor 9. A starting relay comprising

magnets a', a² (Fig. 4) is adapted to shift two three-switch sets to control the operation of motor a at two predetermined speeds to vary the rate of discharge of the sand from said tank according to the speed of operation of the projector. A similar two-speed electric motor b is adapted to drive the bottom r under tank 11 for feeding sand from said tank onto the conveyor 9. A starting relay comprising magnets b', b² (Fig. 4) and two three-switch sets, is provided for controlling the operation of motor b at two predetermined speeds to vary the rate of discharge of sand from tank 11 to conveyor 9. A two-speed electric motor c is provided for driving the bottom r of tank 11^a to feed sand from said tank onto conveyor 9. A starting relay comprising magnets c', c² is provided for controlling the operation of motor c at two predetermined speeds to vary the volume of sand fed from said tank onto conveyor 9. A two-speed electric motor d is provided for conjointly driving conveyor belts 9 and 9^a through gearing, and to drive them at the same surface speed. A starting relay comprises magnets d', d² and two three-switch sets for controlling the operation of motor d and its speed to drive belts 9 and 9^a at the two different speeds for delivering sand to the projector at the rate at which it is fed from the supply tanks.

Each of the motors a, b, c and d is of the three-phase two-speed type for the operation of the motors at two predetermined speeds, for example, 1200 and 1800 R. P. M., and these motors are automatically controlled so that when the projector motor g is operated at high speed the motors a, b, c and d will be operated at a correspondingly high speed for the delivery of a sufficient volume of sand to keep the projector supplied while it is operating at high speed and so that when the projector is operated at its low speed the motors a, b, c and d will be operated at a correspondingly lower speed to properly vary the volume of sand delivered to the projector.

Current is supplied by line-conductors e, e' and e² which are connected respectively to stationary trolley rails f, f', f². Trolley wheel f⁵, f⁶, f⁷ are mounted on carriage o' so as to travel with the projector and engage said rails to supply current to the motor g on the projector and other motors 50 which are adapted to travel with carriage o'. A fourth trolley rail f⁸ is provided and engaged by a trolley wheel f⁹ also carried by carriage o' for supplying current to circuits for controlling the motors of the sand-delivery system. The motors a, b, c and d receive current from the line conductors e, e' and e² through their starting relays.

A switch mechanism m is mounted on the projector-casing adjacent the operator's seat 24 for controlling the operation of the stationarily mounted motors a, b, c and d of the sand-delivery system. This mechanism m also controls the motor g for driving the projector and the pump motor h which are mounted to travel with carriage o' which travels relatively to the sand-delivery system. This switch mechanism is connected to the trolley-wheels f⁵, f⁶, f⁷ and f⁸, as illustrated in Fig. 4, and comprises a manually shiftable lever m' movable between a series of eight stations; a segmental contact 35 engageable by a contact 33 on lever m' for controlling the operation of magnet h' which controls the pump motor h; a segment 37 engageable by a contact 34 on lever m' for controlling magnet g' which controls the operation of the projector motor g at low speed; a segmental contact 38 engageable by

a contact 34 on lever m' for controlling the magnet g^2 which controls the high-speed operation of the projector motor g ; and a series of six contacts 63 engageable respectively by a contact 32 on lever m' for transmitting impulses for operating an auto transformer or relay n for shifting switch mechanism l which is stationarily mounted and is adapted to selectively control the relays for motors a , b , c and d for driving the sand-delivery mechanism at high speed and low speed by the selective movements of the lever m' by the operator on seat 24.

Switch mechanism l comprises rotatable segments 42, 43, engageable by stationary contacts 46, 47 respectively; contacts 44, 45, rotatable with segments 42, 43; a series of contacts 62 engageable by rotary contact 45; and a pair of segments 49, 50, successively engageable by contact 44. Contact 45 is rotatable between seven stations and at station 3 engages one of the contacts 62 for energizing magnet a' for starting and controlling the low speed operation of the motor a for feeding facing sand to the conveyor 9. At station 4, contact 45 engages another contact 62 for energizing magnets b' or c' for starting and controlling the low speed operation of motors b and c , respectively, for feeding facing sand to conveyor 9. At station 6, contact 45 engages another of the contacts 62 for energizing magnet a^2 for controlling the high-speed operation of motor a for feeding facing sand to conveyors 9, 9^a. At station 7, contact 45 engages another of the contacts 62 for energizing magnets b^2 or c^2 , for controlling the high-speed operation of motors b or c . Contact 44 is engageable with segments 49 and 50 for circuits through magnets d' , d^2 , respectively, for controlling the low and high-speed operation of the motor d which drives the conveyors 9, 9^a of the sand delivery mechanism.

An autotransformer or relay n is provided for rotating the contacts 44 and 45 of switch mechanism l by electrical impulses responsive to the movements of the lever m' of the switch mechanism m . This relay n comprises a pair of magnets 53, 54; an armature-lever 56, the ends of which are shiftable by said magnets, respectively; pawls 57 and 58 connected to the ends of lever 56; and a toothed wheel n' adapted to be advanced step-by-step in clockwise direction by the pawl 57 and in counterclockwise direction by the pawl 58 responsive to impulses through the magnets 54, 53, respectively. The relay n also comprises a coil n^2 , the ends of which are connected by conductors 59 and 60 to the trolley-rails f , f^2 , respectively. A conductor 61 connects the trolley-rail f^3 to the helices of magnets 53, 54. The other ends of said helices are connected to the coil n^2 between its ends, as illustrated in Fig. 4, so that when current of 220 volts is used, current of 165 volts will pass through the helix of magnet 54 when the current flows to the coil from conductor 61 to conductor 60 and the current through the helix of magnet 53 will be reduced to 55 volts. The higher voltage through magnet 54 will cause it to operate lever 56 and pawl 58 to shift wheel n' one step in counterclockwise direction. When current flows to coil n^2 from conductor 59, the helix of magnet 53 will receive 165 volts while magnet 54 will receive only 55 volts, which will cause lever 56 to operate pawl 57, so as to advance wheel n' one step in clockwise direction. Toothed wheel n' is fixed to the rotatable segments 42, 43 and contacts 44, 45 of switch mechanism l so that they will be rotated step-by-step in either direction by the relay n to selectively control the

operations of motors a , b , c and d from the lever m' of the switch mechanism m which travels with the projector.

Contacts 30, 31 of switch mechanism m are provided to swing on the pivot of and relatively to lever m' and their outer ends are normally pressed by springs m^3 into a centralized position and out of engagement with said lever. When the handle of lever m' is shifted in counterclockwise direction, it will compress the lower spring m^3 and engage contact 31 and, when shifted in the opposite direction, it will compress the upper spring m^3 and engage contact 30.

Contacts 63 of switch mechanism m are disposed to be engaged by contact 32 on lever m' between the indexed stations at which the lever is stopped. As a result, when the handle of lever m' is shifted in counterclockwise direction between stations 2 and 8 of said lever, contact 31 will be engaged by lever m' and between each of said stations, contact 32 will make momentary contacts with the contacts 63 and at each contact 63 will establish a circuit for energizing magnet 54 to operate contacts 44, 45 and segments 42 and 43 one step in counterclockwise direction. During shift of the handle of lever m' in clockwise direction from stations 8 to 2, lever m' between each two stations will engage contact 30 and momentarily establish a circuit through one of the contacts 63 for energizing magnet 53 for operating contacts 44, 45 and segments 42 and 43 step-by-step in clockwise direction. The circuit for impulses to magnet 54 for imparting operative strokes to pawl 58 to rotate wheel n' in counter-clockwise direction will be as follows: trolley-wheel f^5 , conductor 66, contact 31, lever m' , contact 32, one of the contacts 63, conductor 68, trolley-wheel f^8 , trolley rail f^3 , conductor 61, magnet 54, coil n^2 , conductor 59, and trolley-rail f . The circuit for impulses through magnet 53 for operating the toothed wheel n' and contacts 44 and 45 of mechanism l in clockwise direction will be as follows: trolley-wheel f^7 , conductor 64, contact 30, lever m' , contact 32, one of the contacts 63, conductor 68, trolley-wheel f^8 , trolley-rail f^3 , conductor 61, the helix of magnet 53, coil n^2 , conductor 60, and trolley-rail f^2 .

The switch mechanism m , which is mounted to travel with the projector, controls the motor g for operating the projector at predetermined high and low speeds and the motor h for driving the pump motor, and is adapted, by the selective movements of lever m' , through the switch mechanism l and relay n , to control the operation of the motor d for driving the sand-conveyors 9, 9^a, the motor a for feeding facing sand, and the motors b and c for feeding backing sand onto the conveyors at predetermined high and low speeds.

When lever m' is at station 1, as shown in Fig. 4, all of the motors will be idle; at station 2, pump-motor h will be started and operated at low speed; at station 3, motor g for driving the projector and motor d for driving the sand-conveyors 9, 9^a will be operated at the low predetermined speed; at station 4, the projector motor g , the motor d for driving the conveyors 9, 9^a, and the motor a for feeding facing sand to said conveyors will be operated at low speed; at station 5, the projector motor g , the motor d for driving the sand conveyors 9, 9^a and the motor b or c for feeding backing sand onto the conveyors will be driven at low speed; at station 6, projector motor g and the motor d for the endless conveyors 9, 9^a will be operated at high speed and the motors

*a, b and c will be idle; at station 1, the projector motor *g*, the motor *d* for driving the sand-conveyors and the motor *a* for feeding facing sand to said conveyors will be driven at high speed; and at station 8, the projector motor *g*, the motor *d* for driving the sand-conveyors 9, 9^a and either one of the motors *b* or *c* for feeding backing sand onto the conveyors, will be driven at high speed.*

*The operation will be as follows: when lever *m'* of switch mechanism *m*, which is movable with and by the operator seated at the projector, is in its normal position, as illustrated in Fig. 4, all of the circuits for the operation of the motors for driving the sand delivery apparatus and the motors on the projector will be open and all of said motors will be idle. When the operator shifts lever *m'* to station 2, the motors *h* for driving the pump for supplying oil under pressure to the hydraulic mechanism (not shown) for shifting the projector arm 13 and jib 12 will be started while the motor *g* for operating the projector is idle. At station 2, the following circuit will be established for energizing magnet *h'* to close the switches for the operation of motor *h*, viz: trolley-wheel *f'*, conductor 64, contact 33 on lever *m'*, segment 35, conductor 36, the helix of magnet *h'*, conductor 65, and trolley-wheel *f*. Motor *h* will then start and remain in operation until lever *m'* is again restored to its normal position at station 1. When lever *m'* is at station 2, all motors except motor *h* will remain idle.*

*When the operator shifts lever *m'* to station 3, the following circuit will be established to start the motor *g* for driving the projector, viz: trolley-wheel *f'*, conductor 64, contact 34, segment 31, conductor 38', the helix of magnet *g'*, conductor 66 and trolley-wheel *f*. Magnet *g'* will then close the contacts for the operation of motor *g* at the predetermined low speed desired for the sand projector, for example 1200 R. P. M. The projector will continue to operate at this speed while lever *m'* remains at stations 3, 4 and 5. When the operator shifts lever *m'* from station 2 to station 3, switch mechanism *l* will be operated one step in counterclockwise direction to start the motor *d* for driving the conveyors 9, 9^a at the low predetermined speed. The lever *m'* between stations 2 and 3 momentarily establishes the following circuit, viz: trolley-wheel *f*, conductor 66, contact 31, lever *m'*, contact 32, contact 63, conductor 68, trolley-rail *f*, conductor 61, the helix of magnet 54, a portion of coil *n*, conductor 60 and trolley-rail *f*. Magnet 54 will impart a stroke to lever 56 and shift pawl 58 to rotate wheel *n'* and contacts 44 and 45 one step in counterclockwise direction. Contact 44 will then engage segment 49 and close the following circuit for starting the motor *d* to drive the conveyors 9 and 9^a at low speed, viz: line conductor *e*, trolley-rail *f*, conductor 59, contact 46, segment 42, contact 44, segment 49, conductor 70, the helix of magnet *d'* and conductor *e*. Magnet *d'* holds the switches for the operation of the motor *d* at low speed closed while contact 45 is at stations 2, 3 and 4 to deliver sand to the projector at the desired rate for the operation of the projector at low speed, for example 1200 R. P. M.*

*When the operator shifts lever *m'* from station 3 to station 4, the circuit through magnet 54 will again be momentarily closed at contact 31 to again rotate wheel *n'* and contacts 44, 45 of switch mechanism *l* one step in counterclockwise direction. The following circuit will then be established for starting the motor *a* for the delivery of facing sand from tank 10 to conveyors 9, 9^a*

*at the desired rate for the low speed operation of the projector, viz: line conductor *e*, conductor 78, contact 47, segment 43, contact 45, contact 62 at station 3 of switch mechanism *l*, conductor 74, the helix of magnet *a'*, conductor 70, segment 49, contact 44, segment 42, contact 46, conductor 59, trolley-rail *f*, and line conductor *e*. Magnet *a'* will then close the switches for the operation of motor *a* at the predetermined low speed for delivering facing sand from tank 10 onto the conveyors 9 and 9^a for delivery to the projector.*

*When it is desired to supply backing, in lieu of facing, sand to the projector for delivery into the flasks at low speed, the operator will shift lever *m'* to station 5 of the switch mechanism *m* which will again close the circuit for again operating the magnet 54 to advance wheel *n'* another step in counterclockwise direction, and shift contact 45 into engagement with the contact 62 at station 4 of the switch mechanism *l*. This will interrupt the circuit for magnet *a'* at contact 45 to stop motor *a* and close the following circuit for starting and operating motor *b* at low speed, viz: conductors *e*, 78, contact 47, segment 43, contact 62 at station 4 of switch mechanism *l*, conductor 76 in which one of the members of switch *k* is included, the helix of magnet *b'*, conductor 70, segment 49, contact 44, segment 42, contact 46, conductor 59, trolley-rail *f*, and conductor *e*. Magnet *b'* will then close the switches for the operation of motor *b* for the delivery of backing sand to the conveyors 9, 9^a, at the desired rate for the low-speed operation of the projector.*

*When the supply of backing sand from tank 11 is exhausted and it is desired to supply sand from tank 11^a, switch *k* will be reversed and the magnet *c'* will be energized to close the circuits for the operation of motor *c* at low speed. The circuit will then be from conductor 76 through the upper member of switch *k*, conductor 77 and magnet *c'*, in lieu of magnet *b'*.*

*When it is desired to operate the projector at high speed, for example, 1300 R. P. M., the operator will shift lever *m'* to station 6 of switch mechanism *m*. This will interrupt the circuit for magnet *g'* at contact 34 and segment 37 and close a circuit through magnet *g* for closing the switches for establishing circuits for operating the motor *g* at high speed. When lever *m'* is shifted to station 6, the following circuit will be established for energizing magnet *g*, viz: trolley-wheel *f'*, conductor 64, contact 34, segment 38, conductor 40, helix of magnet *g*, conductor 66 and trolley-wheel *f*, so that magnet *g* will close the switches for starting and operating the motor *g* at high speed.*

*The circuits for the operation of the projector motor *g* at high speed will remain closed while lever *m'* is at or between stations 6, 7 and 8 of switch mechanism *m*, so that the projector motor will remain running. When lever *m'* is shifted from station 5 to station 6, the circuit through lever *m'* and contact 31 will again be closed to operate magnet 54 for the rotation of wheel *n'* and contacts 44 and 45 in counterclockwise direction to station 5 of mechanism *l*. At said station of mechanism *l*, contact 45 will be disconnected from the circuits for magnets *a* and *b* and *c*, so that the motors for feeding sand to the conveyors 9, 9^a will be idle. When contact 44 leaves segment 46 between stations 4 and 5, it will interrupt the circuit through magnet *d'* to open the switches for the low-speed operation of motor *d*. When contact 44 is at station 5 of*

mechanism *l*, it will engage segment **50** and establish the following circuit for starting motor *d* at high speed, viz; conductor **59**, contact **46**, segment **42**, contact **44**, segment **50**, conductor **79**, the helix of magnet *d*², conductor **78** and conductor *e*². Magnet *d*² will then close the switches for the operation of motor *d* at high speed.

When lever *m'* is shifted to station **7**, the circuit through contact **31** and lever *m'* will again be closed. Magnet **54** will again be operated to rotate contacts **44**, **45** of mechanism *l* one step in counterclockwise direction and bring said contacts to station **6** of mechanism *l*. The following circuit will then be established for closing the switches for the high-speed operation of the motor *a*, viz: conductor **78**, contact **47**, segment **43**, contact **45**, contact **62** at station **6**, conductor **81**, helix of magnet *a*², conductor **79**, segment **50**, contact **44**, segment **42**, contact **46**, and conductor **59**. Magnet *a*² will then close the switches for the high-speed operation of the motor *a* for delivering facing sand to the conveyors **9** and **9^a**.

When it is desired to deliver backing sand at the high rate to the projector, the operator will shift lever *m'* to station **8** of switch mechanism *m*, which will again close the circuit for the operation of magnet **54** to rotate wheel *n'* one step in counterclockwise direction and shift contacts **44**, **45** to station **7** of mechanism *l*. The following circuit will then be established for the high-speed operation of motor *b* for delivering backing sand onto the conveyor, viz: conductors *e*², **78**, contact **47**, segment **43**, contact **45**, contact **62** at station **7**, conductor **82** in which one member of switch *k* is included, the helix of magnet *b*², conductor **79**, segment **50**, contact **44**, segment **42**, contact **46**, conductor **59**, trolley-rail *f*, and conductor *e*. Magnet *b*² will then close the switches for operating one motor *b* at high speed. If the switch *k* is reversed, the magnet *c*² will be energized to close the switches for motor *c*, in lieu of those for motor *b*.

When the handle of lever *m'* is shifted in clockwise direction between stations **8** and **2**, said lever will engage contact **30** and successively establish circuits for impulses through magnet **53** for shifting wheel *n'* and contacts **44**, **45** step-by-step in clockwise direction. This circuit for each impulse will be as follows: trolley-wheel *f*⁷, conductor **64**, contact **30**, lever *m'*, contacts **32**, **63**, conductor **68**, trolley-wheel *f*⁸, conductor **61**, the helix of magnet **53**, a portion of coil *n*², conductor **59**, trolley-rail *f*, and conductor *e*. Each operation of magnet **53** will rock lever **56** to cause pawl **57** to rotate wheel *n'* one step in clockwise direction and correspondingly rotate contacts **44** and **45** of mechanism *l* so that, during the return of lever *m'* to its normal position, the circuits previously described for the operation of all of the motors at the intermediate stations, will be established in reverse order. Fixed stops **51** are provided to limit the movement of contact **44** and fixed stops **52** are provided to limit the movement of contact **45**.

The invention is not to be understood as restricted to the details set forth, since these may be modified within the scope of the appended claims, without departing from the spirit and scope of the invention.

Having thus described the invention, what I claim as new and desire to secure by Letters Patent is:

1. Control mechanism for apparatus including a rotary sand projector mounted on a structure

adapted to travel over a floor, stationarily mounted apparatus for delivering sand from a source of supply to the projector when it is moved to different positions over the floor, a stationarily mounted plural-speed electric motor for driving the sand delivery apparatus and an electric plural-speed motor for driving the projector, mounted to travel with the structure, said control mechanism comprising a manually and selectively operable control device mounted to travel with the projector, and means operable by said device for conjointly controlling the operation and speed of the motor for driving the delivery apparatus at different speeds and operation of the motor for driving the projector at different speeds.

2. Control mechanism for apparatus including a rotary sand projector mounted on a structure adapted to travel over a floor, stationarily mounted apparatus for delivering sand from a source of supply to the projector when it is moved to different positions over the floor, a stationarily mounted electric motor for driving the sand delivery apparatus and an electric motor for driving the projector, mounted on and to travel with the structure, said control mechanism comprising a manually and selectively operable switch device mounted to travel with the projector, means controlled by said device for controlling the operation of the motor for driving the projector, stationarily mounted switch mechanism for conjointly controlling the operation of the motor for driving the sand delivery apparatus at different speeds, and means, responsive to impulses controlled by said device, for shifting said switch mechanism.

3. Control mechanism for apparatus including a rotary sand projector mounted on a structure adapted to travel over a floor, stationarily mounted apparatus for delivering sand from a source of supply to the projector when it is moved to different positions over the floor, a stationarily mounted plural-speed electric motor for driving the sand-delivery apparatus and an electric plural-speed motor for driving the projector, mounted to travel with the structure, said control mechanism comprising a manually and selectively operable switch device mounted to travel with the projector, for controlling the operation of the motor for driving the projector at different speeds, a stationarily mounted switch mechanism for conjointly controlling the operation of the motor for driving the sand-delivery apparatus at different speeds, and means controlled by said device, for shifting the switch mechanism to control the operation and speed of the motor for driving the sand-delivery apparatus.

4. Control mechanism for apparatus including a rotary projector mounted on a structure adapted to travel over a floor, stationarily mounted conveying-means for delivering sand to the projector when it is moved to different positions over the floor, a stationarily mounted plural-speed electric motor for driving the sand-conveying means, means for feeding sand from a source of supply onto the conveying-means, an electric plural-speed motor for driving said sand-feeding means, and an electric plural-speed motor for driving the projector, mounted on and to travel with the structure, said control mechanism comprising a manually and selectively operable control device mounted to travel with the projector, and means controlled by said device for conjointly controlling the operation of the motor for driving at different speeds the conveying-means, the operation of the motor at different speeds for driving

the sand-feed means, and the operation and speed of the motor for driving the projector.

5. Control mechanism for apparatus including a rotary projector mounted on a structure adapted to travel over a floor, stationarily mounted conveying-means for delivering sand to the projector when it is moved to different positions over the floor, a stationarily mounted plural-speed electric motor for driving the sand-conveying means, means for feeding sand from a source of supply onto the conveying-means, an electric plural-speed motor for driving the sand-feeding means, and an electric plural-speed motor for driving the projector, mounted on and to travel with the structure, said control mechanism comprising a manually and selectively operable control-switch device mounted to travel with the projector, means controlled by said device for conjointly controlling the operation and speed of the motor for driving the projector, stationarily mounted switch mechanism for controlling the operation and speed of the motors for driving the conveying-means and the sand-feed means, and means responsive to impulses controlled by said device for shifting said switch mechanism.

6. Control mechanism for apparatus including a rotary projector mounted on a structure adapted to travel over a floor, stationarily mounted conveying means for delivering sand to projector when it is moved to different positions over the floor, a stationarily mounted plural-speed electric motor for driving the sand-conveying means, means for feeding sand from a source of supply to the conveying-means, an electric plural-speed motor for driving said sand-feeding means, and an electric plural-speed motor for driving the projector, mounted on and to travel with the structure, said control mechanism comprising a manually and selectively operable control switch device mounted to travel with the projector, means controlled by said device for conjointly controlling the operation and speed of the motor for driving the projector, stationarily mounted switch mechanism for controlling the operation and speed of all of the stationarily mounted motors, and means operable by electric impulses controlled by said device, for selectively shifting the switch mechanism to control the operation and speed of the stationarily mounted motors.

7. Control mechanism for apparatus including a rotary projector mounted on a structure adapted to travel over a floor, stationarily mounted conveying-means for delivering sand to the projector when it is moved to different positions over the floor, a stationarily mounted plural-speed electric motor for driving the sand-conveying means, mechanisms for feeding sand from a plurality of sources of supply to the conveying-means, plural-speed electric motors for driving said sand-feeding mechanisms, respectively, and an electric plural-speed motor for driving the projector, mounted on and to travel

with the structure, said control mechanism comprising a manually and selectively operable switch device mounted to travel with the projector, means controlled by said device for conjointly controlling the operation and speed of the motor for driving the projector, stationarily mounted switch mechanism for controlling the operation and speed of all of the stationarily mounted motors, and means operable by electric impulses controlled by said device, for selectively shifting the switch mechanism to control the operation and speed of the stationarily mounted motors.

8. Control mechanism for apparatus including a rotary sand projector movably mounted on a structure adapted to travel over a floor, stationarily mounted conveying-means for delivering sand to the projector when it is moved to different positions over the floor, a stationarily mounted plural-speed electric motor for driving the sand-conveying means, mechanism for feeding sand from a source of supply to the conveying-means, an electric plural-speed motor for driving the sand-feeding mechanism, an electric plural-speed motor for driving the projector, mounted to move with the projector and to travel with the structure, said control mechanism comprising a manually and selectively operable control device mounted to move with the projector, means controlled by said device for conjointly controlling the operation and speed of the motor for driving the projector, stationarily mounted switch mechanism comprising a rotatable member for controlling the operation and speed of all of the stationarily mounted motors, and a stationary relay comprising a toothed wheel connected to rotate said member and magnets for shifting the wheel step-by-step in opposite directions to shift the rotatable member, said control device comprising switch contacts for controlling the movement of the wheel in opposite directions.
